DESIGN FOR A BATH SPRAY HEAD

Charles T. Manville, Woodbury, and Paul S. Madsen, Bethany, Conn., assignors to The Seamless Rubber Company, New Haven, Conn., a corporation of Connecticut

Application February 21, 1946, Serial No. 126,822

Term of patent 14 years

(Cl. D91—1)

To all whom it may concern:

Be it known that we, Charles T. Manville and Paul S. Madsen, citizens of the United States, residing respectively in Woodbury, in the county of Litchfield, and Bethany, in the county of New Haven, and State of Connecticut, have invented a new, original, and ornamental Design for a Bath Spray Head, of which the following is a specification, reference being had to the accompanying drawing, forming part thereof, in which

Fig. 1 is a face view of a bath spray head showing our new design;

Fig. 2 is an edge view;

Fig. 3 is a rear view;

Fig. 4 is a section on line 4—4 of Fig. 2; and

Fig. 5 is an edge view taken at right angles to Fig. 2.

We claim:

The ornamental design for a bath spray head, substantially as shown.

CHARLES T. MANVILLE.

PAUL S. MADSEN.
